(57) **CLAIM**

The ornamental design for a conical shape insert for pump bottles, as shown and described.

DESCRIPTION

FIG. 1 is a top perspective view of a conical shape insert for pump bottles, showing my new design;

FIG. 2 is a side elevational view of my design, all sides are identical;

FIG. 3 is a top plan view of my design;

FIG. 4 is a bottom plan view of my design; and,

FIG. 5 is an exploded top perspective view thereof, shown in a position of use with an exemplary cylindrical pump container.

The broken lines represent environmental subject matter of an exemplary pump container as well as parts of the article. None of the broken lines form part of the claim.
